UNITED STATES PATENT OFFICE.

EVERETT G. LIVESAY, OF PRINCETON, WEST VIRGINIA.

MAIL-CRANE.

1,159,849.

Specification of Letters Patent.

Patented Nov. 9, 1915.

Application filed May 1, 1915. Serial No. 25,264.

To all whom it may concern:

Be it known that I, EVERETT G. LIVESAY, a citizen of the United States, residing at Princeton, in the county of Mercer and State of West Virginia, have invented a new and useful Mail-Crane, of which the following is a specification.

The present invention appertains to mail cranes, and aims to provide a novel and improved appliance of that character.

It is the object of the invention to provide means for mounting the crane, whereby the arms or jibs of the crane may normally stand parallel with the track, so as not to interfere with passing trains, and means being provided whereby the engineer or other person upon the mail train can operate the crane mechanism so that the crane arms or jibs will swing toward the track before the mail car reaches the crane, in order that the mail collector may properly catch the mail bag supported by the crane.

Another object of the invention is the provision of a crane structure embodying unique means for mounting or supporting the crane properly, whereby the crane is normally held in inoperative position, means being provided whereby the crane may be released by a device carried by the train, and means then coming into play for swinging the crane to operative position with respect to the train.

It is also within the scope of the invention to provide a device of the character indicated, which is improved generally in its construction and details, to enhance the utility thereof, the device being readily installed upon the road bed in connection with ordinary or special trains, and being comparatively simple, non-encumbering and inexpensive in construction, as well as being thoroughly practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is an elevation of the structure

with the crane in operative position. Fig. 2 is another elevation taken at right angles to the line of view in Fig. 1. Fig. 3 is a section on the line 3-3 of Fig. 1. Fig. 4 is an enlarged sectional detail of the stand which receives and supports the mast of the crane. Fig. 5 is a sectional detail taken on the line 5-5 of Fig. 4. Fig. 6 is a fragmental view illustrating a modified form. Fig. 7 is a fragmental elevation of the modification. Fig. 8 is a sectional detail on the line 8-8 of Fig. 6. Fig. 9 is a diagrammatic view illustrating a further modification.

In carrying out the invention, there is provided a suitable base adapted to be bolted or otherwise fastened upon the ties or other foundation, and including an upstanding tubular stand 1 receiving the lower end 70 portion 2 of the mast 3 of the crane, whereby the mast is journaled for rotation within the stand 1. The mast 3 carries the usual crane arms or jibs 4 which are provided at their free ends with fingers 5 for receiving 80 the mail bag, and it is preferable to provide spring pressed latches 6 pivoted to the arms or jibs 4 for normally holding the mail bag upon the fingers 5, but to allow the mail bag to be readily drawn off of the said fingers. 85 The mast 3 also preferably carries a suitable counter weight 7 at that side opposite the arms 4, whereby the same is balanced to rotate easily. A handle 8 is pivoted to the mast 3 above the stand 1 for manually 90 swinging the crane when desired, the handle 8 normally swinging downwardly adjacent the stand, and being readily swung upwardly when the mast 3 is to be rotated.

The mast 3 has a head or enlargement 9 at its lower end which is rounded to seat on a plug 10 threaded or otherwise engaged in the lower end of the tubular stand 1, whereby the mast 3 will rotate freely within the stand, and with little friction. The 95 mast 3 is provided with a drum or reel 11 adjacent yet spaced slightly above the upper end of the stand 1, and the drum 11 has an outstanding lug 11' which is arranged to strike a stop 11' carried by the upper end 100 of the stand 1, when the same is swung to operative position. A cord or flexible element 12 is wound or passed around the drum 11 and has one end attached to the lug 11', and the cord 12 is passed over a pulley or 105 guide member 13 carried by the upper end of the stand 1. A suitable weight 14 is at

tached to the free end of the cord 12, and has a tendency to unwind the cord 12 from the drum 11, and to thus swing the crane to operative position.

5 A latch 15 is slideable through the lower end portion of the stand 1 and a suitable bearing 16 is carried by the base, and a coiled wire expansion spring 17 is disposed upon the latch or latch bolt 15 between the bearing 16 and a collar 18 secured upon the latch, whereby the spring 17 tends to project the latch inwardly or into engagement with the head 9 of the mast. The head 9 is provided with a notch 19 at one side into which the latch 15 is projected when the crane is swung to an inoperative position with the arms or jibs 4 parallel with the track. In this manner, the latch 15 holds the crane in inoperative or normal position against the influence of the weight 14.

In order that the latch 15 can be released by the train man, the free end of the latch 15 is connected by a rod or link 20 with one arm of a bell crank lever 21 fulcrumed adjacent the track, and the other arm of the lever 21 is connected by a rod or link 22 with a bell crank lever 23 fulcrumed adjacent one rail of the track. This lever 23 is provided with a cam 24 and is adapted to be engaged by a tappet 25 carried by the locomotive of the train, although the tappet 25 may be carried by any car. The tappet 25 is preferably so carried by the train that it may be raised or retracted ordinarily, and so that it may be lowered to engage the cam 24 when the crane is to be released.

In operation, when the mail bag is applied to the crane, the crane is swung by means of the handle 8 to inoperative position, in which event the latch 15 will spring into engagement with the head 9 of the mast to hold the arms or jibs 4 parallel with the track. This will prevent the crane projecting toward the track and will also prevent the crane from interfering with traffic. When the mail train approaches the crane, the mail clerk or trainman depresses or lowers the tappet 25 so that it will engage the cam 24, and the cam 24 is therefore depressed. Through the medium of the connection between the lever 23 and latch 15, the depression of the cam 24 will retract the latch 15 and thus release the crane. As a result, the weight 14 will swing the crane to operative position, and the lug 11^a in striking the stop 11' will properly limit the movement of the crane when it reaches operative position. The crane arms or jibs 4 thus project toward the track, in order that the mail bag may be readily removed. The crane may then be swung out of the way by the attendant, for a new operation.

The present crane structure is desirable in that it enables the crane to be normally swung out of the way so as not to interfere

with passing trains, although the crane may be readily brought into operative position when the mail train passes. The present device also embodies advantageous features of construction and operation which are desirable and effective for the intended purposes.

In the modification illustrated in Figs. 6, 7 and 8, the mast 3' of the crane has its lower end portion 2' journaled within the tubular stand 1', and is adapted to swing in either direction from operative to inoperative position, which is desirable when trains traveling in opposite directions are to receive mail from the same crane. In this form, the mast 3' is provided with an angularly extending arm 12' immediately above the stand 1', and a cord or flexible element 12^a is attached to the free end of the arm 12'. The cord 12^a passes between a pair of pulleys 13^a carried by a bracket 13^a attached to the stand 1', and a weight 14' is attached to the free end of the cord 12^a. The mast 3' may thus swing in either direction away from operative position, since the cable 12^a will in either event pass over one of the pulleys 13' and raise the weight 14'. A spring pressed latch bolt 15' is slideable through one wall of the stand 1' and is engageable in one or the other of a pair of notches 19' provided in the end portion 2' of the mast. When the mast 3' is turned to one position, the latch bolt 15' engages one notch 19', and when the mast is swung to the opposite position, the latch bolt engages the other notch, for holding the crane in inoperative position. The latch bolt 15' may be released by the mechanism above described, when the mail train approaches the crane, for releasing the mast 3' so that the weight 14' comes into play for swinging the mast to operative position.

In Fig. 9 an electrical means is illustrated for releasing the latch bolt 15^a, said means embodying an electrical circuit 22' including a suitable source of electrical energy and a solenoid 20'. A cam 24' is connected to one end of the circuit 22' and a contact 23' coöperable with the cam 24' is connected to the other end of the circuit, whereby the cam or switch member 24' being normally raised will open the circuit. The latch bolt 15^a is in the form of a core for the solenoid 20', whereby when the cam or switch member 24' is depressed by the mail train to engage the contact 23', the electrical circuit will be closed, and the solenoid 20' being energized will draw the core or latch bolt 15^a thereinto for moving it out of engagement from the crane.

Having thus described the invention, what is claimed as new is:

In a device of the character described, a tubular stand, a crane mast having its lower end portion journaled within said stand, a latch device carried by said stand and en-

gagable with said mast to hold it in either of two inoperative positions, means for releasing said latch device, the said mast having an angularly extending arm immediately above said stand, a flexible element attached to said arm, a pair of pulleys carried by the stand and arranged at the upper end thereof, the flexible element being passed between said pulleys and being adapted to pass over

either one of them, and a weight attached to said flexible element for turning the mast to operative position when the said latch device is released.

In testimony that I claim the foregoing as my own, I have hereto affixed my signature.

EVERETT G. LIVESAY.
